[57] CLAIM

The ornamental design for a wireform for an orthodontic appliance or similar article, as shown and described.

DESCRIPTION

FIG. 1 is a perspective view of a wireform for orthodontic appliances or similar article showing our new design;

FIG. 2 is a front elevational view thereof on an enlarged scale;

FIG. 3 is a rear elevational view thereof, on an enlarged scale;

FIG. 4 is a right side elevational view thereof, on an enlarged scale;

FIG. 5 is a left side elevational view thereof, on an enlarged scale;

FIG. 6 is a bottom plan view thereof, on an enlarged scale;

FIG. 7 is a top plan view thereof, on an enlarged scale. The broken line drawing of an orthodontic appliance is for illustrative purposes only and forms no part of the claimed design.

UNITED STATES PATENT AND TRADEMARK OFFICE
CERTIFICATE OF CORRECTION

PATENT NO. : Des. 314,823
